FLYING-TIME AND LIKE INDICATOR

Howard Clive Mayers, London, England

Application January 17, 1935, Serial No. 2,299
In Great Britain August 22, 1933

2 Claims. (Cl. 161—15)

This invention relates to flying-time and like indicators, such for instance, as those constructed in accordance with my British Patent No. 361,663, of November 26, 1931 and the United States Patent No. 1,967,157, issued July 17, 1934, and it has for its object to provide an improved construction which, although capable of being used so as to give accurate time indications, conveniently in terms of fractions of a minute, is at the same time arranged so as to register for a comparatively long period, usually amounting to several hours.

According to the present invention a clock-work mechanism for a flying-time or like time-integrating device comprises in combination a gear train controlled by an escapement and actuated by a mainspring to which it is connected by a ratchet device, a rotatable trip-time indicating member connected frictionally with the gear train, and a rotatable winding member for simultaneously winding the main spring and resetting to zero the trip-time indicating member, which latter is arranged to rotate a plurality of times for each revolution of the winding member. Preferably the winding member is connected with the trip indicating means through a lost motion device to prevent the transference to the trip time indicating member of any backlash which may be occasioned by the ratchet device. The spindle of the winding member may, if desired, be connected with a spindle of the usual gear train of the clock-work by two sets of gear wheels having identical gear ratios and arranged in parallel, one of said gear wheels being provided with a lost motion device for enabling the indicating member to be reset exactly to zero despite any return movement of the winding member due to any slight backlash in the means used for holding the main spring in its wound condition.

The clockwork mechanism may conveniently comprise an escapement driven from a spring or equivalent through the medium of a gear train, a winding spindle upon which the spring is mounted, said spindle being connected with the gear train through a ratchet device, and to the indicating member through multiplying gear having a coupling permitting lost motion, while the indicating member and the escapement gear train are connected together frictionally so as to permit slipping during the rewinding operation.

The above described mechanism may be associated with a metal capsule for connection with a source of fluid pressure which serves to control the mechanism, while trip hour integrating means may be moved progressively once for each revolu-

tion of the indicating member and may be provided with means which come into engagement with a stop when said indicating means is disposed at zero.

The invention is illustrated by way of example in the accompanying drawings in which

Figure 1 is a diagrammatic sectional elevation through the clockwork mechanism, the spindles of the gear train being shown in the plane of the drawing;

Figure 2 is a front view of the instrument, the dial being partly broken away;

Figure 3 is a sectional side elevation of the instrument to an enlarged scale;

Figure 4 shows the instrument in front elevation;

Figure 5 is a front elevation of the auxiliary main wheel and lost motion device;

Figure 6 is a front elevation of the trip hour integrating means when the instrument is indicating the maximum trip time; and

Figure 7 is a view corresponding to Figure 6 when the instrument is in its fully wound and reset condition.

Referring firstly to Figures 1 and 3, it will be seen that the instrument comprises a cup-shaped casing 10, to the rear wall 11 of which a metal capsule 12 is secured, said capsule being provided with a screw threaded nipple 13 whereby it can be connected with a Venturi or pitot tube in the known manner. The rear plate 14 and front plate 15 accommodate between them a clock-work mechanism which is indicated generally at 16, said front plate 15 being flanged as shown at 17 for supporting a dial 18, while the adjacent part of the casing 10 is formed with slots 19 whereby the dial 18 can be illuminated from a lateral direction. A celluloid strip 20 prevents the access of dirt through the slots 19, while the front of the instrument is closed by glass 21 held in position by means of a bezel 22.

The clockwork mechanism 16, the component parts of which are shown more clearly in Figure 1, comprises a mainspring 24, the outer end 23 of which is secured to a convenient part of the frame, while the inner end is attached to a winding spindle 25 extending through the plate 15 and glass 21 to the outside of the instrument where it is provided with a winding and reset knob 26. Secured fast upon the winding spindle 25 is a ratchet wheel 27 which co-operates with a pawl 28 carried by a main gear wheel 29 in the usual manner, so that as soon as the winding torque is released from the knob 26 the unwinding action of the spring 24 transfers a reverse torque to

the gear train through the main wheel 29. In accordance with the usual clock practice the main wheel 29 meshes with pinion 30 which is frictionally mounted upon a subsidiary spindle 31 owing to the action of a spring 32. The gear wheel 33 formed in one with the pinion 30 is geared through the intermediary of spindles 34 and 35 to an escapement wheel 36, movement of which latter is controlled in the known manner by means of a lever 37 and balance wheel 38 having a spiral spring 39, the whole arrangement being such that the subsidiary spindle 31 is constrained to make one revolution per hour while the clockwork is operating.

15 Operation of the escapement is controlled from this capsule 12 by mechanism corresponding to that disclosed in Figures 1 and 2 of the prior U. S. Patent No. 1,967,157, and including a wire 40 which is normally disposed between two of the teeth of the escapement wheel 36, the arrangement being such that when sufficient air pressure is applied to the capsule 12, as for example when the aeroplane is in flight, the wire 40 is lifted away from the escapement wheel 36 20 by means of a linkage indicated generally at 41, thus rendering operative the clockwork mechanism.

In order to indicate the trip time a hand 50 is carried by a sleeve 51 rotatable upon the winding spindle 25, and is driven at the rate of one revolution per hour from the subsidiary spindle 31, gear wheels 52 and 53 of equal diameter being provided for this purpose. The gear wheel 53 is fast upon the subsidiary spindle 31, while a pinion 54 is similarly secured thereto, said pinion 54 being arranged to mesh with an auxiliary main wheel 55. The gear ratio between the pinion 54 and auxiliary main wheel 55 is equal to that between the pinion 30 and the main wheel 29. A lost motion device is provided between the winding spindle 25 and the auxiliary main wheel 55 as shown in Figure 5, and for this purpose a pin 56 carried by the spindle 25 is arranged to have a limited angular movement relative to the wheel 55.

50 A trip hour integrating device is also provided for recording the number of complete revolutions which have already been made by the hand 50 during the prevailing flight, and for this purpose a pin 57, rigid with the sleeve 51, is arranged to actuate a trip hour disc 58 by means of a star wheel 59, the construction of which latter is shown more clearly in Figures 6 and 7. The teeth of the star wheel 59 are also engaged by a detent spring 60 which provides a snap action, and it will be realized from Figure 7 that as the sleeve 51 rotates once per hour in a clockwise direction the star wheel 59 will be moved in an anti-clockwise direction one step for each hour 60 until the position shown in Figure 6 is reached when a stop 61 fixed to the star wheel 59 encounters a screw head 62 carried by the plate 15. This prevents further operation of the clockwork mechanism and stops the instrument.

65 In resetting the instrument to zero, the knob 26 is rotated in an anti-clockwise direction, and it will be seen that this rewinds the spring 24 at the same time rapidly rotating the hand 50 also in an anti-clockwise direction but at an increased speed due to the gear ratio between the wheels 55 and 54. As the hand 50 reaches the zero indication on the scale during that revolution when the trip hour disc 58 is also registering zero, the parts assume the position 70 shown in Figure 7, thus providing a positive

stop for the winding knob 26. It is very unlikely, however, that when this position is reached the pawl 28 will be firmly seated in one of the teeth of the ratchet wheel 27, so that a slight return movement of the knob 26 is inevitable as the winding pressure is released therefrom. This, however, is not transferred to the hand 50 in a magnified form owing to the manner in which the auxiliary main wheel is mounted, the slight return movement of the spindle 25 causing 10 the pin 56 to assume a position indicated at 56a without influencing the zero setting of the hand 50.

15 As shown in Figures 2 and 3, the instrument is also provided with a total time indicator comprising a series of discs 63, 64, 65 and 66 which are driven by star wheels in the known manner so as to indicate decimals, units, tens and hundreds of hours' flight respectively. The disc 63 is connected with a spindle 67 (see Figure 3) 20 which latter is driven directly from the main wheel 29 so that the total flying time indicator is not returned to zero each time the instrument is reset.

25 The front view of the instrument is shown in Figure 4, from which it will be seen that the hand 50 co-operates with a "minute" scale 10, each minute being divided into quarters for the purpose of enabling accurate time indications to be made.

30 The actual form of the instrument may, of course, be modified to suit the particular kind of service for which it is required, appropriate fixing means being provided for the instrument. Moreover, the calibration of the dial and other 35 indicating means may be arranged to suit requirements, and if desired the trip hour indicator, where such is included, may be adapted to read up to one hundred or more hours. The design described, however, is particularly compact and is efficient in action, especially owing to the fact that the actuation of a single knob enables the instrument to be set rapidly to zero in an accurate manner and at the same time re-winds the spring. 40

45 Any suitable means can, of course, be used for controlling the operation of the instrument according to the apparatus with which it is being used, and in instances where a capsule or diaphragm is incorporated this may be actuated by water, oil or other appropriate liquid having a pressure greater or less than the pressure of the casing within the instrument.

What I claim is:—

1. In a clockwork mechanism, a gear train, a winding shaft, an indicating member rotatable about the winding shaft, a spring coiled about the winding shaft and at one end secured thereto, the gear train including a spindle having a small gear fixed thereon and a large gear rotatable thereon, intermeshing gears carried by the indicating member and spindle, a pinion carried by the large gear and corresponding in size to the small gear, a ratchet disc fixed to said winding shaft, a large running gear loose about 55 the winding shaft and meshing with said pinion, a pawl carried by the loose gear on the winding shaft and engaging teeth of the ratchet disc, a large setting gear loosely mounted on the winding shaft and meshing with the small gear of 60 the spindle for imparting rotation thereto, and a lost motion connection between the winding shaft and the setting gear.

2. In a clockwork mechanism, a gear train, a winding shaft, an indicating member rotatable 75

- about the winding shaft, a spring coiled about the winding shaft and at one end secured thereto, the gear train including a spindle having a small gear fixed thereon and a large gear rotatable thereon, intermeshing gears carried by the indicating member and spindle, a pinion carried by the large gear and corresponding in size to the small gear, a ratchet disc fixed to said winding shaft, a large running gear loose about the winding shaft and meshing with said pinion, a pawl carried by the loose gear on the winding shaft and engaging teeth of the ratchet disc, a large setting gear loosely mounted on the winding shaft and meshing with the small gear of the spindle for imparting rotation thereto, the setting gear having a pocket leading from its shaft receiving opening, and a pin projecting from the winding shaft into the pocket and providing a lost motion connection between the winding shaft and setting gear.

HOWARD CLIVE MAYERS.
